Primary Examiner—B. J. Bullock*Attorney, Agent, or Firm*—Timothy T. Tyson[57] **CLAIM**

The ornamental design for a door hinge for utility vehicles, as shown and described.

DESCRIPTION

FIG. 1 is a top plan view of a door hinge for utility vehicles showing my new design;

FIG. 2 is a left side elevational view, the right side elevational view being the mirror image thereof without the mirror holder;

FIG. 3 is a bottom plan view thereof; and,

FIG. 4 is a rear elevational view, the front elevational view being the mirror image thereof without the hinge tab.

FIG. 1

FIG. 3

FIG. 2

FIG. 4
